UNITED STATES PATENT OFFICE.

JACK F. JACOBSON, OF MOBILE, ALABAMA.

NECKTIE.

1,090,719.

Specification of Letters Patent. Patented Mar. 17, 1914.

Application filed September 29, 1913. Serial No. 792,373.

To all whom it may concern:

Be it known that I, JACK F. JACOBSON, a citizen of the United States, residing at Mobile, in the county of Mobile and State of Alabama, have invented certain new and useful Improvements in Neckties, of which the following is a specification.

This invention relates more particularly to improvements in that class of neckties known to the trade as imperial or flowing-end ties, which are adapted to be tied in what is known as a four-in-hand knot. Such ties are usually made of silk or satin cut on the bias, and in tying, they are very easily pulled out of shape; so easily, in fact, that after they are tied but a few times they become practically useless, and this has greatly detracted from their salability.

The object of the present invention is to obviate the above mentioned defect by transferring the pulling action from the main or ornamental end of the tie to the lining of the tie, and this is done by attaching to the lining an auxiliary tie end of an ornamental or displayable character preferably of the same material as the main or outside material of the adjacent end of the tie. This auxiliary tie end is adapted to be pulled by the user instead of his pulling the main end of the tie, as is now the custom.

My invention further relates to certain features hereinafter described and more particularly pointed out in the claims.

In order to more fully describe my invention, reference will be had to the accompanying drawings wherein:

Figure 1, represents a side elevation partly in section, looking at the back of a tie of the above class embodying one specific form of my said invention; Fig. 2, a longitudinal central section thereof; Fig. 3, an enlarged fragmentary section taken in a plane at right angles to that of Fig. 2, and showing the end of the tie, only, which is provided with my improved end, and Fig. 4, a cross-section on line 4*-4* Fig. 3.

In the accompanying drawings, 1 represents the outer material of the tie, having two main "flowing" ends 2 and 3. Attached to the outer material of the tie, as by stitching 4, at a point intermediate of its ends, after the usual custom, is a lining 5. This lining is usually made of canton flannel or some other material heavier than the outer material of the tie to give body to the same. This lining preferably fits closely along the

folded edges of the outer material, except adjacent one end thereof where it tapers off, as at 6, along both edges toward the end of the tie. To the tapered end of the lining 60 is attached by stitching 7, an auxiliary flowing tapered end 8, preferably of the same material as the main end 2. This stitching is preferably V-shaped, as shown, and points in the direction of the adjacent tie end, the 65 apex of the V coinciding substantially with the center line of the lining. By means of this form of stitching the strain is brought almost entirely on the center line of the lining.

It is intended in using this tie that the wearer shall pull on the auxiliary end 8, rather than on the main end 2, thereby putting all the pull or strain on the lining directly. The main end 2 is not to be grasped 70 or pulled at all, and for this reason may be absolutely saved from the customary injurious effects of being grasped and pulled. Moreover, the auxiliary end 8 being entirely free, except at its point of attachment to the 75 lining, is readily accessible, and since this may be of displayable material, preferably of the same material as the adjacent main end of the tie, it may fly outside of the rear flaps 9 and 10 of the said main end, and not 80 detract from the appearance of the tie. This auxiliary end is itself preferably provided with rearwardly folded flaps or wings 85 11 and 12, after the fashion of the main end 2.

This invention has an additional advantage in that an ordinary flowing tie must be pushed somewhat to one side in order to clasp it with a tie clasp to the shirt. With my improved tie, it is not necessary to thus 95 push it aside in clasping it to the shirt, since the tie-fastener may be attached to the auxiliary end.

Having thus described a specific embodiment of my invention, it is understood that 100 the same is susceptible of modification without departing from the true spirit of the invention.

What I claim is:

1. A necktie having two main ends and a 105 lining made fast to the outer material of the tie intermediate of its ends and having an end detached from the outer material, and an auxiliary tie end attached to said end of said lining but detached from the adjacent 110 main tie end.

2. A necktie having two main flowing

ends and a lining made fast to the outer material of the tie at a point intermediate of said ends and free from said material adjacent at least one of said ends, and an auxiliary flowing tie end attached to said free end of said lining but detached from said outer material except through said lining at said intermediate points of attachment, said auxiliary end adapted to be pulled by the user without pulling the adjacent main end of the tie, thereby transmitting said pull directly through the lining to the outer material of the tie at said intermediate point of attachment, said auxiliary end being of an ornamental character.

3. A necktie having two main ends and a

lining made fast to the outer material of the tie intermediate of its ends and having an end detached from the outer material, and an auxiliary tie end stitched to said end of said lining but detached from the adjacent main tie end, said stitching being directed diagonally inward to approximately the center line of the lining in two directions to form a V-shaped figure, substantially as described.

In testimony whereof I affix my signature in presence of two witnesses.

JACK F. JACOBSON.
